UNITED STATES PATENT OFFICE

170,433

BOTTLE RACK

Alma I. Wahren, Carrington, N. Dak.

Application June 26, 1953, Serial No. 25,667

Term of patent 7 years

(Cl. D58—4)

To all whom it may concern:

Be it known that I, Alma I. Wahren, a citizen of the United States, residing at Carrington, in the county of Foster and State of North Dakota, have invented a new, original, and ornamental Design for a Bottle Rack, of which the following is a specification, reference being had to the accompanying drawing, forming a part hereof.

Figure 1 is a front elevational view of a bottle rack, showing my new design;

Figure 2 is a top plan view;

Figure 3 is an end elevational view; and

Figure 4 is a rear perspective view.

I claim:

The ornamental design for a bottle rack, as shown.

ALMA I. WAHREN.
